SANITARY NAPKIN AND THE LIKE

Catherine L. Matthews, Little Rock, Ark.

Application May 19, 1933, Serial No. 671,804

1 Claim. (Cl. 128—290)

This invention has general reference to sanitary bandages or napkins; but relates more particularly to an absorbent pad for such a device, which pad is formed from absorbent material such as cotton fiber, cellulose or so-called "cellulose cotton", which material may either be in the form of a plurality of superposed layers, or compressed into a unitary pad of suitable thickness.

Various special materials have been devised for the absorbent pads of sanitary napkins and the like, the principal objects of such materials being to combine ready and rapid absorption with uniform distribution of the substance absorbed throughout the pad; and special provision also has been made for partially enclosing such pads in catamenial sacks of "silk rubber" or the like, or backing them with such materials, such sacks or materials ordinarily being intended to be re-used. My present invention does not relate to the use of any specific material for the pad itself, but contemplates that any preferred, suitable absorbent material may be employed. Also, it is not intended that my improved sanitary pad shall be re-used, although re-use would be feasible, since the pad is so reinforced and held together that it would withstand washing or other cleansing operations.

The primary object of the present invention is to improve upon, and overcome the objections to, the sanitary napkins and the like known heretofore, particularly in the following respects:

By providing for such a device an absorbent pad which shall be of form-fitting configuration, preferably with the ends rounded and of substantially the same width as the main portion of the pad;

By providing for such a device a pad having at one side thereof a thin, flexible, moisture-proof backing, which preferably should not extend over the ends or the edges of the pad;

By providing for such a device a pad having such a backing, and with the edges of the backing, and of the main portion of the pad, reinforced by a binder, which preferably should be stitched to the pad;

By providing for such a device a pad having such a backing which preferably is so stitched as to insure that the backing will be firmly secured to the pad, and will lie flat thereupon.

The means by which the foregoing and other desirable objects are accomplished by my present invention, and the manner of their accomplishment, readily will be understandable from the following description on reference to the accompanying drawing, in which:

Fig. 1 is a plan view showing the backing as applied to one side of the pad.

Fig. 2 is a section taken substantially on the line II—II of Fig. 1.

Referring now to the drawing in detail, the reference numeral 5 indicates the body portion of a pad which may be either a plurality of superposed layers or a single unit of compressed cotton, cellulose or the like. In Fig. 2 the pad is shown as a one-piece member, but, as stated hereinbefore, such specific form of construction of the pad body is not involved in the present invention. Numerals 6 and 7 indicate the respective rounded ends of the pad, which are separated from the main portion by similar curvilinear neck sections which are indicated by numerals 8 and 9.

Over the body portion 5 of the pad, a cover or backing 10 is superposed, such cover or backing may have a marginal binder 11, which may be of cloth or any other suitable fabric, and which extends around the edge of the cover or backing 10, the latter preferably being either cellophane, silk rubber, or other light flexible, water-proof material. As indicated in Fig. 2, marginal stitching secures the backing 10 to the pad, preferably extending through the pad, and thereby tending to retain the pad in its original shape. This stitching may also be used to secure the marginal binder. Diagonal lines of stitching, 12 and 13 respectively, also may extend from the respective corners of the backing 10, and not only assist in securing the backing to the pad but also insure its lying flat thereupon.

The end portions 6 and 7 of the pad preferably are substantially of the same width as the main portion 10, since said end portions are utilized as securing means, and therefore should be of sufficient size for the reception of safety pins or the like. By limiting the extent of the backing 10 to the main portion of the pad, the flexibility of the end portions 6 and 7 remains unaffected. It is, of course, contemplated that the moisture-proof backing 10 will be extremely flexible, but it is undesirable that it shall extend over the entire end of the pad, because of the unnecessary quantity of the backing material that such extension would entail, and also because it would be necessary to perforate the backing extended over the ends 6 and 7 in effecting securement of such portions.

As stated hereinbefore, it is not intended that my improved sanitary napkin pad is to be re-used, but the manner of securing the backing to the pad, particularly the marginal stitching 55

extending through the pad, is adapted to retain the shape of the pad if it be washed or otherwise cleansed, and in addition not only to prevent shifting of such backing but curling of edge portions thereof and displacement by wrinkling.

Various modifications of minor details as to the shape or other features of the device disclosed herein, doubtless readily will suggest themselves to others skilled in this art, and I therefore do not desire that my invention shall be construed as being limited to any details not specifically claimed.

Having now fully disclosed the invention, what is claimed is:

15. An absorbent member for a sanitary bandage comprising a flat, relatively elongated flexible pad of absorbent material, of substantially uniform thickness throughout its width and length, and

a flexible, impervious element opposing one face thereof, said element being of substantially equal width, but of less length than said pad, and disposed approximately centrally of the length thereof, leaving substantially equal length tab portions extending therebeyond, the marginal edges of said element being secured to said pad, as by stitching, whereby to secure said impervious element against displacement, and against curling of the side and end edges thereof, said element in width leaving the side edges of said absorbent pad free to perform their absorbent functions, and in length leaving the tab portions of said pad free for ready attachment as to supporting devices, said tab portions being available 10 as a portion of the absorbent surface.

CATHERINE L. MATTHEWS.
